8 Claims. (Cl. 29—86)

This invention relates to mechanism especially adapted for use in removing and inserting the pins and bushings of tracks, such as used in crawler type tractors.

The individual shoes of the tracks for crawler type tractors are held together by means of pins and bushings, which are frictionally held in place. They are assembled, when manufactured, by forcing the pins and bushings into position under extreme pressure, in the region of fifty tons. When these tractors go out into use it is frequently necessary to repair the track in the field and considerable delay and expense are occasioned if it is necessary to return the tractor to the manufacturer for repair. In the past, the repair of the tracks in the field, has been made only with the greatest difficulty due to the extreme pressure under which the pins and the bushings are inserted. The only tools available in the field for the removal of these parts have been a punch and a sledge. The operation has required two men, one to hold the punch and one to swing the sledge. Frequently, the chains, bushings, and track shoes are badly damaged through the operation, becoming so badly battered from the driving as to render them worthless. Often a shoe is so badly battered in removing the pins and bushings that it becomes impossible to reinsert these parts after the repair has been made. Furthermore, it is common for the workman to be injured during the work because one of the men must hold the punch while the other strikes it and it is difficult to hold the shoes securely in a convenient position for driving. In addition to these objections, considerable time is required. On the average, it takes two men in the neighborhood of eight hours to repair a complete track by the methods heretofore in use, while our invention contemplates a device with which the repair may be accomplished in two hours or less without danger of injury to the workman or damage to the parts. Furthermore, the tracks after being removed from the tractor are so heavy and cumbersome that they can be handled only with difficulty so that they cannot economically be fed to a machine for the removal of the pins and bushings. As a result of these factors, it has been a difficult problem to develop sufficiently simple device capable of developing the desired power which did not require excessive movement of the heavy track.

A major object of our invention is the provision of improved mechanism for removing and inserting the pins and bushings from a track.

Another object of the invention is the provision of hydraulically operated means for pushing the pins and bushings of a tractor.

We have also aimed to provide improved means for holding the track while the pins and bushings are being pushed and for guiding the same during the pushing operations.

A further object of the invention is the provision of portable mechanism which may be supported upon the track for the removal of the same from the tractor.

We have also aimed to provide improved means for positioning the mechanism with respect to the track for the pushing operation.

Other objects and attendant advantages will become apparent to those skilled in the art as the following description proceeds and from the accompanying drawings, in which—

Figure 1 is a top view of the machine secured to a track in a position to remove a pin therefrom;

Fig. 2 is a vertical section on the line 2—2 of Figure 1;

Fig. 3 is a section on the line 3—3 of Fig. 2;

Fig. 4 is a fragmentary view showing the manner in which a pin is inserted;

Fig. 5 is a fragmentary elevation of a modified form of machine;

Fig. 6 is a top view of the form shown in Fig. 5;

Fig. 7 is a fragmentary top view of a modified form of machine adapted for pushing bushings;

Fig. 8 is an elevation of the mechanism shown in Fig. 7, the bolster member being in section, and

Fig. 9 is a top view of a second type of bolster for use with bushings.

The form of the invention illustrated in the drawings contemplates a fluid driving unit and a bolster supported upon the driving unit but spaced to serve as an abutment for preventing movement of the work piece when force is applied thereto. While the device is suitable in general for expressing or impressing pins, bushings, and the like from a variety of objects in which they have a press fit, it is particularly adapted for use in assembling and disassembling the tracks of so-called crawler type tractors. To this end, the device is so constructed as to be portable and is arranged in such a manner that the floor may normally serve to support the work piece but being formed to be capable of support directly upon the tractor for removal of the first pin, it being necessary to remove this

pin before the track may be removed from the tractor.

Referring first to Figs. 1 to 4, inclusive, a body 11 is provided with sockets 12 and 13 for the reception of one end of side rods 14 and 15. The threaded pins 10 on opposite sides of the body 11 serve to secure the rods 14 and 15 within the sockets and permit their rapid convenient removal, a bolster, designated generally by 16, being supported upon the opposite ends of the rods. The body 11, shown in section in Fig. 2, is provided with a cylinder 17 between the sockets 12 and 13, a piston 18 being positioned therein for projection outward between the rods 14 and 15 and in a direction parallel therewith. A packing leather 19 is secured to the inner end of the piston 18 and a packing 21 on the inner side of the cylinder surrounds the piston and is held in position by a retaining ring 22. The body 11 is also provided with a well 23 in which is positioned injectors 24 and 25, which pass through the walls of the body and project from the upper side thereof. The injectors are arranged, through differences in stroke and bore, to inject different amounts of liquid from the reservoir into the cylinder 17 upon reciprocation of the plungers 26 and 27. Reciprocation of the plungers 26 and 27 is brought about through forked levers 28 and 29 which are pivotally connected at one end to the body through links 31 and 32 and at an intermediate point to the plungers. Handles 33 and 34 receive the opposite ends of the levers for manual rotation thereof to cause reciprocation of the plungers. The injectors 24 and 25 are so constructed that the fluid in the cylinder 17 may be released for return to the well 23 by abnormal depression of the plungers. Handles 35 pivotally supported on the body serve to facilitate the movement of the device.

The bolster 16 consists of a cross-arm 36 having sockets 37 and 38 for the reception of the ends of the rods 14 and 15, the rods being releasably held therein by means of threaded pins 39, the pins having wings 41 to facilitate the rotation of the pins. Intermediate the sockets 37 and 38 is an opening 42 which serves to receive and guide a plunger rod 43 presently to be more fully described. The opening 42 joins a slot 44 which is provided on its forward end with a marginal slot 45. The slot 45 serves as an abutment against which is received a boss 46 surrounding an opening 47 of a track, designated generally by the numeral 48, the opening 47 serving to receive a track pin 49 with a press fit. The bolster is also provided with an abutment 51 adapted to rest upon the opposite side of the track 48 and connected to the cross-arm 36 by means of a yoke 52 which may advantageously be integral with the cross-arm and the abutment. The abutment is provided with a tapering bore 53 and a counterbore 54, the two bores providing an opening through which the pin 49 may pass as it is expressed from the opening 47 of the track. The inner face of the abutment is provided with a U-shaped slot 55 similar to the slot 45 and best shown in Fig. 3. The open end of the slot is at the lower side of the bolster, the slots 45 and 55 permitting the bolster to be slipped down over the track, the boss 46 moving into the slot 45, and the boss 56 on the opposite side of the track moving into the slot 55. These slots serve to position the openings 54 and 42 with respect to the track, centering the pin 49 so that it will coincide with these openings. Wings 57 and 58

on the yoke 52 extend laterally outward from the latter and are provided with openings 59 and 61 for the purpose of receiving bolts 62. The bolts 62 pass through the openings 59 and 61 and into threaded holes 63 of the track in which manner the bolster may be firmly secured to the track and supported thereon. These bolts will normally be used only when the press is to be supported upon the tractor for the removal of the first pin from the track. The threaded holes 63 are openings through which the cleats of the track are normally secured thereto so that in securing the bolster to the track, it is necessary to remove two adjacent cleats. Screws 64 are threaded into the lower side of the wings 57 and 58 and bear against the upper side of the track, thereby cooperating with the slots 45 and 55 in centering the pin 49 and the openings in the bolster. The screws 64 will be screwed into the wings more or less depending upon the size of the particular track being operated upon.

In order to transmit the movement of the piston 18 to the end of the pin 49, a cross-bar 65 having openings 66 and 67 near opposite ends thereof is positioned upon the rods 14 and 15, the rods passing through the openings 66 and 67, respectively. The openings are sufficiently large to permit the bar to move longitudinally along the rods. The bar 65 thus presses against the end of the piston 18, as shown in Fig. 2. The bar is provided with an opening 68 substantially on the center line of the piston for the reception of the reduced end 69 of the plunger rod 43, the peripheral shoulder 71 bearing 35 against the face of the cross-bar. The opposite end of the plunger rod 43 is reduced in diameter, as shown at 72, so as to be capable of entering the opening 47 in the track and is arranged to bear against the end of the pin 49. 40 Thus, upon projection of the piston 18, the plunger rod 43 is urged against the end of the pin 49 causing it to be expressed from the opening 47 into the opening in the abutment 51. During this operation, the abutment prevents movement of the track 48 by contact of the boss 56 with the abutment in the slot 55. The portion 72 of the plunger rod need not extend the full length of the plunger since it is only necessary to move the pin 49 a short distance to release it from the track. Thus, the press fit between the pin and the track occurs only in the area 73 in which the pin is of greater diameter than throughout the remainder of its length, the portion 73 of the pin having a press fit in the 55 outer ear 74 of one of the track shoes. Coiled springs 75 and 76 surround the rods 14 and 15 and bear at one end against pins 77 and 78 in the rods. The opposite ends of the springs bear against the cross-bar 65, the springs causing the piston 18 to be moved back into the cylinder 17 when fluid pressure is removed by operation of the injectors.

In Figs. 1 and 2, we have shown the device as used for the purpose of removing the first pin 65 from the track when the track is in position upon the tractor. In accomplishing this operation, the device is clasped by the handle 35 and by a handle 79 on the yoke 52, and the bolster is lowered over the track from which two adjacent 70 cleats have been removed. The bolts 62 are then inserted thus securing the bolster firmly to the track. The screws 64 will, of course, have been set to accommodate the particular size of track. The plunger rod 43 is then inserted in 75

the opening 42 and the end 69 thereof is inserted in the opening 68 of the cross-bar 65. At this point upon reciprocation of the plunger 27, which operates the injector of greater capacity, 5 the piston 18 will be rapidly projected until the forward end of the plunger rod 43 comes in contact with the end of the pin 49. If the pin is not held too firmly, continued reciprocation of the plunger 27 will cause the same to be expressed 10 from the opening 47. However, if greater power is required to loosen the pin, the plunger 26 may be reciprocated, whereupon the piston 18 will be projected with less speed but with greater power thereby providing the extra power necessary 15 for loosening the pin. When the pin 49 has been removed sufficiently to remove the portion 73 thereof from the boss 56, operation of the injectors is no longer necessary since the remainder of the pin may be withdrawn with 20 the fingers. At this point, the fluid is released from the cylinder 17 and the piston 18 is retracted by operation of the springs 75 and 76. The expressing operation is then complete and the bolster may be removed from the track. 25 For the removal of the remainder of the pins, the track is removed from the tractor and spread out upon the floor with the cleats downward, as shown in Fig. 8. In this position, the press may be laid flat upon the floor with the bolster resting over the track, the cleats supporting the remainder of the track at such elevation that the press will operate horizontally. This position of the track is shown in Fig. 8. The press may then be rapidly moved from pin to pin without 30 in any way moving the track during the expressing operations. Since the removal of the pins separates the track into a plurality of relatively small shoes, it will be seen that the use of the mechanism described substantially eliminates 35 the necessity for handling a heavy track while it is being disassembled.

As previously stated, the press may be used with equal facility for the purpose of inserting the pins 49 and reassembling the track. Such 40 operation of the device is shown in Fig. 4. In this case the press is lowered over the track with the plunger rod 43 in a position to bear against the portion 73 of the pin to cause the pin to be moved into the opening 47, the bolts 62 being 45 then inserted in the openings 63 on the opposite side of the track.

When very wide tracks are to be operated upon, we have found it convenient to employ the modifications shown in Figs. 5 and 6. In this 50 instance, the rods 14 and 15 are replaced by similar rods 81 and 82 of sufficient length to extend to the side of the track opposite the pushing unit. A bolster having a cross-arm 83 is positioned at the end of the rods which are received in sockets 84 and 85 thereof. Midway between the sockets 84 and 85 is an abutment 86 in the form of a boss projecting toward the track. An opening 87 extends through the cross-arm 83 and the abutment 86 to permit the 55 pin to pass outward when expressed. The abutment 86 is provided with a U-shaped slot 88 similar to the slots 45 and 55, the open end of the slot, however, being at the upper side of the abutment so that the track may be inserted from the top. A plunger rod 89 is employed substantially similar to the plunger rod 43 except that it is of sufficiently shorter length to accommodate the track of greater width. The operation 60 of this modification is substantially the same as that already described.

In Figs. 7 and 8 we have shown a device similar in its general principles of operation to that shown in Figs. 1 to 4, inclusive, but adapted for the purpose of removing the bushings from the track instead of the pins. In this device, the work piece consists only of independent shoes of the track rather than the track as a whole, and, consequently, the wings 57 and 58 of the bolster are unnecessary. The bolster, therefore, consists of a cross-arm 91 and an abutment 92 connected by means of a yoke 93 having a handle 94 thereon. The cross-arm 91 is provided with sockets 95 for the reception of the rods 14 and 15 and with an opening 96 between the sockets 95, the opening immersing 10 on the plain inner face of the arm. The lower surface of the cross-arm is provided with a plurality of serrations or grooves 97 into which the upper edge of the cleat 98 of the shoe 99 fits, these grooves permitting the work piece 15 to move up sufficiently far into the bolster for setting. The abutment 92 is provided with an opening 101 coaxial with the opening 96 of the cross-arm, this opening permitting the bushing 102 of the shoe to pass through the abutment. The lower side of the abutment is tapered, as shown at 103, to permit the abutment to come in contact with the side wall of the shoe between the top plate 104 thereof and the bushing. A plunger rod 105, similar to the 20 plunger rod 43 except for the outer end thereof, is positioned with its inner end in the opening 68 of the bar 65, as previously described. The free end of the plunger rod 105 is provided with a portion 106 of smaller diameter than the remainder thereof to form a shoulder 107. In operation, the portion 106 of the plunger rod moves into the center opening 47 of the bushing and the shoulder 107 comes into contact with the end of the bushing so that when the piston 25 18 is projected outward, the plunger rod will force the bushing out of the shoe by contact of the shoulder 107 against the end of the bushing. A pilot pin 108 is adapted to be positioned in the opening 101 of the abutment and is provided with an end portion 109 of a diameter to be receivable within the bushing, the pin being relieved at 110 for freedom of movement. The pilot pin serves to guide the bushing from 30 the shoe into the abutment opening 101 to prevent damage to the bushing in removing or inserting the same. The relief portion 110 is of such a diameter as to be receivable in the bushing opening 111 so as to guide the end of the bushing past the intersection of metal in the 35 shoe when the bushing is being inserted. Thus, the device shown in Figs. 7 and 8 is essentially the same as that shown in Figs. 1 to 4, inclusive, with the exception that the parts are so shaped as to accomplish the removal and insertion of 40 the bushing rather than the pin.

In Fig. 9, we have shown a modified form of the bushing expressing mechanism. In this form, a cross-arm 112 is positioned on the ends of side rods 81 and 82 and is provided with 45 sockets 113 for the reception of these rods, the rods being secured by means of threaded pins 114, as previously described. An abutment 115 having an opening 116, similar to the opening 101 of Fig. 8, is formed on the cross-arm 112, the abutment being adapted to bear against the side of the shoe in the same manner as shown in Fig. 8. This modification is adapted to function in the same manner as the device in the 50 above-mentioned figure but is designed for use 55 70 75

in expressing the bushings from the shoes of wider tracks, the only functional difference being that the rods 81 and 82 are longer to accommodate the wider shoes and a plunger rod 5 117 identical in shape with the plunger rod 105 is provided, the plunger rod 117 being of shorter length.

It will be seen that we have provided portable mechanism for expressing the pins and bushings 10 from the tracks of crawler type tractors which may be readily moved about from place to place. The press is constructed for use in a horizontal position and is so arranged that the floor serves as the supporting means for the track. As 15 a result of this construction, it is unnecessary to move the track to accomplish the removal of the various pins, the device being susceptible of movement along the track to the position of the pins. The press, resting upon the floor, permits the operator to stand directly over the 20 mechanism for the convenient operation of the injector handles so that it is operated with a maximum of convenience. The device is capable of use not only for assembling and disassembling the track after it is removed from the tractor but is capable of use directly upon the tractor for the purpose of moving the first pin and accomplishing the removal of the track from 25 the tractor. The press is so arranged that interchangeable bolsters and plunger rods may be employed to accommodate the device for use upon a wide variety of work pieces, in this instance accomplishing the removal of not only the pins but of the bushings from tracks of any 30 widths. The further feature of the device is that the piston and plunger rod are automatically returned to their retracted position by the release of the pressure in the cylinder, thereby increasing the speed of operation of the device. 35 The press may be used with equal facility for both assembling and disassembling the track. As a result of the operation of the device, the pins, bushings and shoes of the track are not in any way damaged, being smoothly expressed and impressed without being in any way battered or 40 depreciated through the operation. Furthermore, the device permits the accomplishment of this without any danger of injury to the operator and at a much greater rate of speed than 45 has heretofore been possible. It permits the work to be accomplished by a single workman in substantially one-fourth of the time previously required for two men, thereby substantially reducing the cost of repair operations on this 50 type of machinery.

While we have thus described and illustrated a specific embodiment of our invention we are aware that numerous alterations and changes may be made without materially departing from 60 the spirit of the invention or the scope of the appended claims, in which we claim:

1. A press of the character described comprising a body provided with a hydraulic piston adapted to be projected in a pressing stroke, a 65 plunger shaped to be positioned with an end against a frictionally held element of a work piece and positioned to be moved by said piston to move said element, and a bolster supported on and spaced from said body to prevent movement of the work piece when force is applied to said frictionally held element, said bolster comprising a cross-arm spaced from and supported at spaced points on the body, an opening intermediate said spaced points to guide the 70 plunger, an abutment spaced from the cross-arm

for the reception of the work-piece therebetween, and means fixedly connecting the cross-arm and the abutment.

2. A press of the character described, comprising a pressing unit, a plunger, means on said pressing unit for moving the plunger in a pressing stroke against the end of a frictionally held track element, a bolster connected to said pressing unit for holding the track against movement under the force of said plunger, said bolster having an opening for the passage of said frictionally held element, and means operable for locating said bolster with said opening and said element in alignment on tracks of different thickness for the passage of said element. 15

3. A press of the character described comprising a pressing unit, a plunger, a bolster connected to said pressing unit adapted to span a track having frictionally held elements and bosses surrounding the same, said bolster being 20 arranged to provide abutments at opposite sides thereof, said abutments having sockets for the reception of said bosses and openings for the passage of said pushing member and said frictionally held elements, and means for moving 25 said plunger in a pressing stroke to insert or remove said frictionally held elements.

4. A press of the character described comprising a pressing unit having a cylinder, a piston, means for injecting fluid to said cylinder to move said piston in a pressing stroke, spaced side arms on said unit, a bolster supported upon 30 said side arms to act as an abutment for a work-piece, a cross-bar slidably supported on said side arms in a position to be moved by said piston during the pressing stroke, and a plunger supported on said cross-bar in a position to engage a frictionally held element of said work-piece, said plunger being movable with said cross-bar to move the frictionally held element 35 with respect to the work-piece.

5. A press of the character described comprising a hydraulic pressing unit shaped to rest in an operative position on the floor and having a movable piston, a handle arranged to project 40 said piston upon reciprocation and shaped to be reciprocated by an operator standing over the unit, a pair of arms shaped to interchangeably support any of a plurality of bolsters in 45 spaced relation to said piston, a bolster for holding a work-piece, a plunger acting between the piston and the work-piece for transmitting a pressing pressure to the latter, means carried by said arms for supporting any of a plurality of plungers of different shape characteristics in 50 operative relationship with said piston and accomplishing different pressing operations, and means carried by said arms for returning the piston from its projected position. 55

6. In a portable press of the character described, bushing pressing mechanism comprising an abutment adapted to abut against a work-piece having a bushing opening, said abutment having an opening larger than said bushing opening, pilot means shaped to be passed 60 through the opening in the abutment and into the opening of the work-piece, and bushing to pilot the bushing during the movement thereof, and means for pressing the bushing through the bushing opening. 65

7. In a portable press, a bolster comprising a cross-arm and an abutment adapted to rest on opposite sides of a work-piece, and means for connecting said cross-arm and said abutment, said abutment having means for centering the 70 75

work-piece, and an opening for the passage of a member expressed from the work-piece, and said cross-arm having an opening for the reception of an expressing plunger, and means for supporting the bolster.

5 8. A portable press shaped to rest upon the floor for removing pins and bushings from tractor tracks when resting on the floor free of the tractor comprising a hydraulic pressing unit 10 having a movable piston, a handle on the top of said unit arranged to project said piston upon reciprocation and shaped to be reciprocated by

an operator standing over the unit, a bolster for holding the track in a desired position, means for connecting the bolster to the unit, means acting between the piston and the work-piece for transmitting a pressing force from the former to the latter, and means on the press for supporting the same on the track while the latter is positioned on a tractor for removing a pin from the track, to remove the track from the tractor.

JOHN HERBERT ABRAMSON.
